US00D928143S

(12) **United States Design Patent** (10) **Patent No.:** **US D928,143 S**
(45) **Date of Patent:** **** Aug. 17, 2021**

(54) **PORTABLE INFORMATION HANDLING SYSTEM**

(71) Applicant: **Dell Products L.P.**, Round Rock, TX (US)

(72) Inventors: **Jihun Yeom**, Seoul (KR); **Eid-Beng Goh**, Taipei (TW); **Shang-Zu Hsieh**, New Taipei (TW)

(73) Assignee: **Dell Products L.P.**, Round Rock, TX (US)

(**) Term: **15 Years**

(21) Appl. No.: **29/723,514**

(22) Filed: **Feb. 7, 2020**

(51) **LOC (13) Cl.** **14-02**

(52) **U.S. Cl.** **D14/315**
USPC **D14/315**

CLAIM

The ornamental design for a portable information handling system, as shown and described.

DESCRIPTION

FIG. 1 is a front perspective view of the portable information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof in an open position;

FIG. 9 is a rear lower perspective view thereof in an open position; and,

FIG. 10 is a rear lower perspective view thereof in a closed position.

Broken lines shown in the drawings illustrate portions of the portable information handling system, and form no part of the claimed design.
